UNITED STATES PATENT OFFICE.

JOHN VOLLMAN, OF RACINE, WISCONSIN.

CONCEALED HINGE.

1,070,754.

Specification of Letters Patent. Patented Aug. 19, 1913.

Application filed October 10, 1912. Serial No. 724,992.

To all whom it may concern:

Be it known that I, JOHN VOLLMAN, a citizen of the United States, residing at Racine, in the county of Racine and State 5 of Wisconsin, have invented certain new and useful Improvements in Concealed Hinges; and I do declare the following to be a full, clear, and exact description of the invention, such as will enable others skilled in the art 10 to which it appertains to make and use the same.

This invention relates to improvements in hinges and particularly to concealed hinges.

One object of the invention is to provide 15 a concealed hinge having an improved construction of detachably connected members adapted to be readily separated to permit the removal of the door or other object supported by the hinge.

Another object is to provide a hinge of 20 the character described which will be simple, strong, durable and inexpensive in construction, efficient and reliable in operation and having means whereby the detachable members thereof may be securely fastened against casual disengagement.

With these and other objects in view, the 25 invention consists of certain novel features of construction, combination and arrangement of parts as will be more fully described and claimed.

In the accompanying drawings; Figure 1 is a detail horizontal sectional view of a portion 30 of a door and its supporting frame showing one of my improved hinges engaged therewith; Fig. 2 is a vertical sectional view taken on the line 2—2 of Fig. 1 and with the parts as shown in dotted lines in this figure; Fig. 3 is an irregular vertical section through the door frame and stationary member of the hinge taken on the line 3—3 of Fig. 2; Fig. 4 is a detail perspective view of the pivotal member of the hinge; Fig. 5 is a front view of the keeper or door member of the hinge.

Referring more particularly to the drawings 1 denotes the door and 2 denotes the door frame to which my improved hinge is applied. In the edge of the door frame is 50 formed a recess or mortise 3 with which is engaged the frame or stationary member 4 of the hinge. The frame or stationary member 4 comprises a plate having therein a centrally disposed rectangular opening 5. On the inner side of the plate at the upper 55 and lower edge of the opening 5 are in-

wardly extending horizontally disposed parallel bearing lugs 6 in which are secured the ends of a vertically disposed pintle 7. Between the lugs and one edge of the plate is 60 formed a reinforcing web 8 and in the outer side of the plate below the opening 5 is a recess or depression 9 the purpose of which will be hereinafter described. In arranging the frame member 4 the lugs 6 will project 65 back into the mortise 3 while the plate on which the lugs are formed will be set into the outer edge of the door frame so that the outer surface of the plate will form a flush engagement with the adjacent surface of the 70 edge of the door frame as shown. When thus arranged the frame member 4 is securely fastened by screws or other suitable fastening devices as shown.

Pivots engaged with the pintle 7 and 75 adapted to swing between the lugs 6 and through the opening 5 in the plate of the stationary member 3 is the swinging or pivotal member 10 of the hinge. The pivotal member 10 comprises a substantially right 80 angularly formed plate having on its inner end an enlarged head 11 provided with a central vertically disposed passage 12 adapted to receive the pintle 7 whereby the member 10 is pivotally secured to the frame or 85 stationary member 4 of the hinge. The opposite end of the pivotal member 10 is slightly curved as shown and has its extremity shaped to form a foot 13 having a flat outer surface and which extends downwardly a short distance below the member to 90 form a lug 14 in which is arranged a screw hole 15 the purpose of which will be hereinafter described. On the upper end of the flat surface of the foot 13 is a vertically 95 disposed dovetail shaped attaching lug 16 by means of which said pivotal member is detachably engaged with the door member 17 of the hinge.

The door member 17 of the hinge 100 comprises a flat plate which is secured to the inner edge of the door or other object 1 to be supported by the hinge and which is set into said edge and secured by screws or other fastening devices, whereby the outer 105 surface of the plate is flush with the edge of the door as shown. In the door member or plate 17 is a vertically disposed tapered slot 18 the edges of which are beveled to form a dovetail shaped recess. The slot 18 110 connects at its lower end with a rectangular opening 19 in the plate, said opening being

slightly larger than the outside dimensions of the lug 16 on the pivotal member 10 of the hinge.

In applying the hinge the stationary or frame member thereof, together with the pivotal member, is secured in the frame of the door in the manner described while the door member or plate 17 is arranged and secured in the edge of the door in the manner described. After the parts of the hinge have been thus arranged the door is held in position to engage the opening 19 in the door member or plate 17 with the dovetail shaped lug 14 of the pivotal member of the hinge, after which the door is lowered thus engaging the tapered slot 18 with the lug. When the door member of the hinge has thus been engaged with the pivotal member, said door member and the door will be hingedly supported by said pivotal member and will be permitted to swing to closed and open positions as clearly indicated in full and dotted lines in Fig. 1 of the drawings.

In order to prevent the casual disengagement of the door member of the hinge from the lug 16 of the pivotal member and at the same time permit the door member and door to be removed when desired, I provide a fastening screw 20 which is engaged with the screw hole 15 in the lug 14 of the pivotal member 10 and is driven through the opening 19 in the door member of the hinge and into the edge of the door, said screw thus firmly securing the pivotal member of the hinge to the door member and positively preventing the door from being lifted and removed until the screw 20 has been taken out. When the door is swung to a closed position the lug 14 is adapted to engage the recess 9 in the outer side of the attaching plate of the frame member of the hinge so that said lug will not interfere with the closing of the door.

It is obvious that when the pivoted member 10 which is carried by the door frame 2 is properly connected to the door member 17, the extended lugs 14 to which the screw 20 passes, entirely covers the basal portion of the opening formed in the door member, thereby presenting a finished connection of the parts and further preventing dust from gaining access to said opening.

While a hinge constructed in accordance with my invention may be employed for a number of purposes the same is particularly

adapted for use in connection with doors of carriage or automobile bodies to permit the doors to be readily removed when necessary in the construction and finishing of the bodies and which when the body is entirely finished and painted and the doors hung for the last time the hinge members may be securely fastened in the manner described to prevent further removal of the door until the fastening devices of the hinges are removed.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined and claimed.

Having thus described my invention, what I claim is:

A concealed hinge comprising a door member, the same consisting of a plate having formed therein an aperture provided with a basal large receiving opening and a tapering extension forming a continuation thereof, a hinged member having a dove-tailed lug adapted for interlocking engagement with the upper portion of the aperture formed in the plate which is secured to the door member, an apertured lug forming a part of said hinged member and projecting below the dove-tailed lug thereof and adapted to cover the receiving basal portion of the aperture in the plate, a frame member having an opening formed therein to receive the hinged member, the latter being mounted to one side of said opening in the frame member, and received thereby when the door is in a closed position, and a screw passed through the apertured lug and through the basal portion of the opening in the plate and into the door member whereby the parts are securely attached and the basal portion of the opening in the plate entirely covered.

In testimony whereof I have hereunto set my hand in presence of two subscribing witnesses.

JOHN VOLLMAN.
